[57] ABSTRACT

A flame tube for a gas turbine engine comprises a tubular element having an inlet and an outlet at opposite ends thereof. A frusto-conical baffle is mounted at the inlet of the tube element so as to direct air entering the inlet against the wall of the tube element. A plurality of vanes are secured to the baffle and to the tube element so as to locate the latter with respect to the baffle. The vanes are mounted by means of a plate and a bush on a chamber within which the flame tube is mounted. The bush receives a fuel atomizer for injecting fuel into the tube element through an axial opening in the baffle and the air which passes into the tube element via the axial opening has a swirl imparted thereto by the vanes.

FIG.1.

FIG.2.

FLAME TUBES

BACKGROUND OF THE INVENTION

This invention relates to flame tubes for gas turbine engines, and has an object to provide a flame tube in a convenient form.

SUMMARY OF THE INVENTION

According to the invention, a flame tube for a gas turbine engine comprises a tube element provided at opposite ends with an inlet and an outlet, a baffle within the tube element adjacent the inlet and adapted to direct air entering the inlet against the tube element wall, said baffle having a through-passage therein, a plurality of vanes secured to the baffle and the tube element to locate the latter with respect to the baffle, said vanes being arranged to impart a swirling motion to air directed through said through-passage and mounting means secured to said vanes, said mounting means being adapted to receive a fuel atomizing device and to engage a structure upon which the flame tube, is in use, located, said atomizing device injecting fuel into the tube element via said through-passage.

An example of a flame tube according to the invention will now be described with reference to the accompanying drawings in which:

BRIEF DESCRIPTION OF THE DRAWINGS

FIG. 1 is a section through a flame tube, and FIG. 2 is a section on line 2-2 in FIG. 1.

DETAILED DESCRIPTION OF THE INVENTION

The flame tube has a tube element 10 provided with an inlet 11 and an outlet 12. Within the inlet end of element 10 is a baffle 13 of generally frusto-conical form and having an axial through-passage 14. Secured to the upstream side of baffle 13 is a reinforcing ring 23. Secured to ring 23 are a plurality of vanes 15, which are also secured to the tube element 10. As seen in FIG. 2 at their inner ends 15b vanes 15 are tangential to an imaginary circle which is of somewhat greater diameter than the passage 14. Each vane 15 has an outer portion 15b which extends radially with respect to the axis of the passage 14. A further portion 15c of each vane 15 extends from the portion 15b to lie against the wall of element 10. A reinforcing portion 15d extends from the portion 15c to lie against and reinforce the portion 15b of an adjacent vane 15, to reinforce the radial portions of the next adjacent vanes. Secured to the portions 15a of the vanes is a mounting comprising a circular plate 16 and a bush 17 secured to the plate 16 and axially aligned with the tube element 10.

The bush 17 is adapted to receive a fuel atomizer shown generally at 18. Bush 17 is externally threaded to receive a nut 19 by means of which the mounting is 55

secured to an end plate 20 of a chamber within which the flame tube is mounted. The plate 16 abuts the end plate 20 whereby any load on the tube element 10 is transferred via the vanes 15 to the end plate 20.

The tube element 10 has slots 21 through its wall intermediate the inlet 11 and outlet 12. Holes 22 also extend through the wall of element 10 downstream of slots 21.

In use, fuel is supplied to the flame tube via fuel atomizer 18 and air under pressure is supplied to the chamber surrounding the flame tube. Air enters the flame tube via passage 14 and is also directed against the wall of element 10 by the baffle 13. The portions 15a of vanes 15 impart a swirling motion to the air passing into the tube element 10 through the axial passage 14 internally of the baffle 13. Secondary combustion air and dilution air enter the flame tube via slots 21 and holes 22 respectively.

I claim:

1. A flame tube for a gas turbine engine, comprising a tube element provided at opposite ends with an inlet and an outlet, a baffle within the tube element adjacent the inlet and adapted to direct air entering the inlet against the tube element wall, said baffle having a through-passage therein, a plurality of vanes secured to the baffle and the tube element to locate the latter with respect to the baffle, said vanes being arranged to impart a swirling motion to air directed, through said through-passage and mounting means secured to said vanes, said mounting means receiving a fuel atomizing device and engaging a structure upon which the flame tube, is in use, located, said atomizing device injecting fuel into the tube element via said through-passage.

2. The flame tube as claimed in claim 1, wherein each vane has a portion which extends so as to lie against an outer portion of an adjacent vane thereby to reinforce that outer portion.

3. The flame tube as claimed in claim 1, wherein each vane has a portion which lies against the tube element 40 wall.

4. The flame tube as claimed in claim 1, wherein the mounting means comprises a plate secured to an inner portion of each vane and a bush secured to the plate and adapted to be detachably secured to the structure and to receive the fuel atomizing device.

5. The flame tube as claimed in claim 4, wherein the bush is externally screw-threaded to engage a nut rigidly connected with said structure.

6. The flame tube as claimed in claim 1, wherein each vane has an inner end portion tangential to an imaginary circle of somewhat greater diameter than the through-passage, with said inner end portions imparting the swirling motion to the air directed through the through-passage.
